[57] CLAIM

The ornamental design for a bottle or similar article, as shown and described.

DESCRIPTION

FIG. 1 is a front elevational view of a bottle or similar article showing my new design, the rear elevational view being a mirror image thereof;

FIG. 2 is a top plan view thereof;

FIG. 3 is a bottom plan view thereof;

FIG. 4 is a left-side elevational view thereof;

FIG. 5 is a right-side elevational view thereof; and

FIG. 6 is a cross-sectional view, on an enlarged scale, taken along the line 6—6 of FIG. 1.

FIG. 1.

FIG. 5.

FIG. 4.

FIG. 2.

FIG. 3.

FIG. 6.
